UNITED STATES PATENT OFFICE

2,377,533

CONTAINER

Harry F. Waters, New York, N. Y.

Application July 16, 1943, Serial No. 494,939

4 Claims. (Cl. 229—3.5)

This invention relates to improvements in containers and more particularly to containers principally made of paper or cellulose products which are liquid proofed. This application is a continuation in part of my application Serial No. 232,292, originally filed Sept. 29, 1938, for Container.

One of the principal objects of the invention is to provide an improved wax treated paper container especially adapted for food products which is provided with a liner that is not only moisture proof, but which is adapted to be sterilized without deterioration of its strength or moisture proof qualities.

Another object of the invention is to provide an improved wax coated paper container which is flexible, may be folded from a blank to a unit capacity container, which may be steam sterilized, and which is externally impervious to moisture after heat treatment comparable to the pasteurization of milk.

A still further object of the invention is to provide a pre-fabricated wax treated paper blank suitable for forming into liquid tight packages for storing and transporting milk and other liquid food products, such blank being flexible and having a resistance to moisture after forming to a unit container, and after a heat treatment with steam for desired sterilization, so that the blank may be sterilized and the products placed in the container can be pasteurized in situ.

Further objects and advantages of my invention will appear from the following disclosure of a preferred form of embodiment of my invention taken in connection with the attached drawings illustrative thereof, and in which:

Fig. 1 is a perspective view of the container with parts broken away;

Fig. 2 is a horizontal cross section on the line 2—2 thereof;

Fig. 3 is a plan view of a paperboard blank for making the novel containers herein and showing the gluing pattern;

Fig. 4 is a plan view showing the initial step of adhering the bottom sections of the blank according to the gluing plan of Fig. 3;

Fig. 5 is an elevation showing the partially folded blank of Fig. 4 completely folded;

Fig. 6 is a view similar to Fig. 5 showing the edge gluing tabs folded over and onto adjacent wall panels;

Fig. 7 is a bottom plan view of the structure of Fig. 6, showing the folded-over fin seams at the edges of the flat-folded container and showing the bottom fold lines;

Fig. 8 is a vertical section taken on line 8—8 of Fig. 6 and showing the bottom folds in flat-folded position of the container;

Fig. 9 is a bottom view of the erected container of Fig. 6 and showing the bottom panels in snap-down, container-forming and locking position;

Fig. 10 is a perspective of the bottom structure and associated side wall structure of the erected container;

10 Fig. 11 is an elevation of the top of the container showing the top-forming segments of the side walls in open position;

Fig. 12 is a view similar to Fig. 11 showing a special gluing pattern, and

15 Fig. 13 is a view similar to Fig. 12 showing the completed top structure with all panels secured in place.

It is well known that wax coated milk bottles and similar food containers have not proved entirely successful as they cannot be sterilized and in many States where strict regulation is in force, they cannot be used. Not only is it necessary to provide for sterilization and also to prevent moisture absorption, but it is also essential in order to meet competitive costs, that the container be of flexible material so that they can be shipped in an inexpensive knock-down condition.

I have now found that I can make a container which meets all the necessary commercial requirements as well as being inexpensive and of attractive appearance. In accordance with a preferred form of embodiment of my invention as shown in Fig. 1, this includes the use of a supporting structure for the container, generally indicated at 10, which supporting structure may be of a heavy Kraft paper, a molded pulp material, or other suitable material, but the one I prefer is heavy ground wood board. This constitutes the intermediate layer 12.

Within this container, I use a wax paper liner 14 which is preferably a bleached sulphite paper approximately 30 pound weight and of good wet strength. This is treated with a coating material of wax base which is firm, non-tacky, and moisture proof at 225° F. to provide an inner coating 14' thereon. Coating materials of such character are well known to those skilled in the art and are disclosed, for example, in U. S. Patent No. 2,054,115 to Abrams et al. Inner coating 14' is also resistant to moisture at this temperature and I can steam sterilize the package just prior to its use, which is especially desirable. The coating may be provided by means of any conventional procedure and is preferably applied by

a suitable coating machine to a thickness in the range of 0.001 of an inch or less.

The outer coating 16 is also preferably constituted of a wax material but ordinarily it does not require a coating material of such a high melting point or resistance to temperature as the inner coating. I also find that I can pasteurize milk directly in the container which is a very economical and desirable procedure. In such case, the outer coating must be a wax material which is still non-tacky at about 160° F. for considerable time to assure stability in the long period of pasteurization which is about 45 minutes at 143° F.

If desired, the outer coating 16 can also be coated on the supporting layer 12 by a coating machine or otherwise, and it is preferably firmly adherent thereto. On the other hand, the inner liner 14 may or may not be integrated with the supporting layer 12. If all of the layers are to be laminated, the process described in my issued United States Patent No. 2,125,758 issued on August 2, 1938, is preferred.

The novel construction hereinabove may be prepared from special blanks, all as illustrated in Figs. 3, to 13, inclusive. In this construction, a special blank 20, of generally rectangular shape, is provided with a plurality of main wall panels 21, 22, 23 and 24 defined by central longitudinal fold line 25, side longitudinal fold lines 26 and 27, end or top fold lines 28 and bottom or transverse fold line 29 parallel to fold lines 28. The bottom panel structure, designated herein by the numeral 30, includes the longitudinal fold lines recited above and a central transverse fold line 32 dividing the blank 20 horizontally into two symmetrical portions. The bottom section 30 is provided further with diagonal fold lines 33, 34, 35 and 36 severally extending from central longitudinal fold line 25 substantially adjacent to transverse fold lines 29, and terminating at lateral longitudinal fold lines 27, likewise substantially adjacent to the transverse median fold line 32 of the blank. The bottom section will be seen to be divided into a central diamond or lozenge having generally triangular sections 37, and four triangular sections 38 around the periphery thereof, and bounded by cross fold lines 29, and side fold lines 26, 27, as well as the diagonal fold lines 33, 34, 35 and 36, previously noted. At the extremities of the several panels 21, 22, 23 and 24, are formed integral tabs or top sections 40 and 41, the sections 40 being integral with the diagonally opposite panels 21, 24 while the end or tab sections 41 are severally integral with the diagonally opposite panels 22, 23. Tabs 40 and 41 are both generally triangular and are formed with symmetrical fold lines 42 forming isosceles triangles with the fold lines 28. A pair of triangular tabs 43 having central longitudinal fold lines 44 are formed exteriorly of the fold lines 42. A V-shaped cut-out 45 is formed in tabs 41, while an integral V-shaped panel 46, separated from an end tab 48 by fold line 49, is formed in a corresponding position of tabs 40.

The inner surface of the blank 20, as shown in Fig. 3, is provided with marginal edges 18 on which are disposed glue lines or strips 50, co-extensive therewith. The triangular bottom panel sections 38 are severally provided with triangular glue lines 51 which are substantially co-extensive with the marginal edges of the several triangular sections.

Referring now to Fig. 4 the blank 20 is shown in the position obtaining when the bottom sec-

tion is folded along transverse fold line 32 and the glue lines or patterns 51 are contacted with and secured to the adjacent panels 21, 22, 23 and 24 and the contacting sections of glue lines 50 of the bottom panels are severally contacted with the glue lines of the fins 18. When this occurs the panel or triangular sections 38 are permanently secured together leaving the bottom sections 37 free but in folded-up condition, as shown more in detail in Fig. 8.

The next step in the formation of the novel container is the folding of panels 23, 24 along transverse fold line 29, over and on panels 21, 22 with the glue lines 50 of side panels 18 being 15 mutually contacted and securing the structures in interlocked condition. As shown in Fig. 5, the outer portions of side walls or segments 18 are severally provided with strands or glue lines 52, which secure the fins 18 to the adjacent wall 20 panels when the fins are folded thereagainst on fold lines 26, 27, respectively. The flat-folded container will assume the condition shown in Fig. 6, with the bottom panel 30 folded up internally thereof as shown in Figs. 7 and 8. Upon 25 squaring up the container, as by applying compression along diagonally opposed fold lines 26, 27, the side walls will square up to assume the position shown in Figs. 9 to 13, with the bottom panel 30 being snapped downwardly along central fold line 25 and the transverse fold line 32, so that it assumes a generally dished shape with its segments locked to provide stiffening and supporting braces or sections for the side walls of the package.

Referring now to Figs. 11 to 13, inclusive, there is shown the method of sealing the top of the container. The tabs or triangular sections 40, 41 are secured in the following manner. The inner surfaces of tabs 40 are provided with adhesive 40 53, and the outer surfaces of sections 43 of closure panels 40 are provided with glue patterns 54. The opposed tabs or terminal sections 40 are moved inwardly of the mouth of the container and the glued tabs 48 are secured together, as 45 shown in Fig. 12. Thereafter, the side wall tabs 41 are moved inwardly so that their side sections 43 are engaged and contacted with the gluing patterns 54 on the similarly positioned sections of closure panels 40. This gives a completely liquid- 50 proof top seal, as shown in Fig. 13, with no leakage possible, due to the interrelation of the closure parts.

It will, of course, be understood that the sealing of the top of the container will be effected 55 only after the package has been filled with commodities. The package is adapted to handle liquid commodities of various sorts including milk and milk products as well as powdered or granulated food materials. In use, the terminal tab 60 48 may be torn off, exposing the contents to view and permitting the pouring out of the same.

The containers may be initially fabricated and shipped in the flat-folded form shown in Fig. 6 and thereafter erected at the place of filling and 65 the filled container sealed in the manner described above.

The invention is particularly suitable for collapsible milk containers of the type described in my co-pending application Serial No. 255,030, 70 filed February 7, 1939, but it will be apparent that it is suitable for any form of paper food container. By paper, I include pulp and related cellulose products, and containers made by moulding or in the folding of blanks. It is of especial 75 advantage with prefabricated blanks which can

be completed as to body, liner and coating prior to shipment to the dairies or other place of use. In such case, the user need only spring open the blank to container size, sterilize the interior and fill with the desired product. No wax coating or other expensive step need be carried out by the consumer. The economy of initial material, and subsequent inexpensive sterilization are substantial advantages of this product.

While I have described a preferred form of embodiment of my invention, I am aware that other modifications may be made thereto, and I therefore desire a broad interpretation of my invention within the scope and spirit of the description herein and of the claims appended hereinafter.

Having now particularly described and ascertained the nature of my said invention, and in what manner the same is to be performed, I declare that what I claim is:

1. In a container for foodstuffs including milk which comprises a cellulosic supporting body, and a fluid-tight coating at least on the inner surface of said supporting body, said coating being constituted of a material of wax base having a melting point sufficiently high to retain its fluid-tight character after exposure to the sterilizing action of steam for several minutes, the said container having a generally square cross section with rectangular wall panels and a snap-down bottom panel with diagonally opposed fin seams joining adjacent wall sections, said fin seams being folded over on a wall panel and secured thereto, the improvements comprising a top closure having generally triangular tabs formed at the tops of the wall panels and integral therewith, two of the said tabs having terminal lugs or ears secured together and the angular sides of the tabs having folded pleats interfolded and secured to like sections of adjacent tabs whereby to form a hermetic top closure.

2. In a fluid-tight container adapted to withstand sterilizing and pasteurizing temperatures and pressures which comprises a supporting body of fibrous cellulosic board, a flexible inner liner within said supporting body, and a fluid-tight coating on the inner surface of said liner and on the outer surface of said supporting body, said coating consisting of a material of wax base having a melting and softening point sufficiently high to remain fluid-tight and substantially non-tacky after exposure to sterilizing and pasteurizing

agents, the improvements comprising a container having a generally square cross section with rectangular wall panels and a snap-down bottom panel with diagonally opposed fin seams joining adjacent wall sections, said fin seams being folded over on a wall panel and secured thereto.

3. In a fluid-tight food container capable of withstanding sterilizing temperatures and pressures which comprises a main body of fibrous cellulosic board, an inner flexible liner in said main body, a fluid-tight coating on the inner surface of said liner and on the outer surface of said supporting body, both of said coatings being constituted of a material of wax base, said coating on the liner having a melting point sufficiently high to remain fluid-tight after exposure to sterilizing agents at a temperature of at least 212° F. for several minutes, and said outer coating having a melting point sufficiently high to remain fluid-tight and non-tacky after exposure to pasteurizing influences at a temperature of about 145° F. for periods of about one-half hour to one hour, the improvements comprising a container having a generally square cross section with rectangular wall panels and a snap-down bottom panel with diagonally opposed fin seams joining adjacent wall sections, said fin seams being folded over on a wall panel and secured thereto.

4. A flat-folded paperboard container erectable into square cross-section, comprising a sheet of material folded on itself and having the opposite edges of its opposed faces secured together to provide an open mouth, the opposed faces having parallel longitudinal score lines defining front and back wall panels and side wall panels, an infolded bottom section having a top fold line perpendicular to the longitudinal axis of the container, the marginal edges of the flat-folded container and bottom being adhesively secured to form lateral fins, and the said fins being folded in and secured to and on the side walls of the container, the bottom being provided further with angular fold lines extending from the fin fold line to the wall panel fold lines and to define corners which are severally adhered to adjacent wall panels, the diagonal fold lines of the bottom being adapted to arch downwardly upon squeezing sides of the flat-folded container to form a bottom, and thereby erect and maintain the container in its open position.

HARRY F. WATERS.
